DESIGN FOR A GARMENT HANGER

Jerome H. Rotheraine, Philadelphia, Pa.

Application April 27, 1944, Serial No. 113,384

Term of patent 7 years

(Cl. D33—8)

To all whom it may concern:

Be it known that I, Jerome H. Rotheraine, a citizen of the United States, residing at Philadelphia, in the county of Philadelphia and State of Pennsylvania, have invented a new, original, and ornamental Design for a Garment Hanger, of which the following is a specification, reference being had to the accompanying drawing, forming part thereof,

In the drawing:

Fig. 1 is a side elevational view of a garment hanger, showing my design;

Fig. 2 is a front elevational view; and

Fig. 3 is a rear elevational view thereof.

I claim:

The ornamental design for a garment hanger, substantially as shown.

JEROME H. ROTHERAINE,
